UNITED STATES PATENT OFFICE.

EDWARD W. BRIGGS, OF BROOKLYN, AND JOHN D. WALTON, OF NEW YORK, N. Y.

PUNCH.

SPECIFICATION forming part of Letters Patent No. 295,227, dated March 18, 1884.

Application filed March 30, 1883. (No model.)

To all whom it may concern:

Be it known that we, EDWARD W. BRIGGS, of Brooklyn, in the county of Kings and State of New York, and JOHN D. WALTON, of the city and county of New York, in said State of New York, have invented certain Improvements in Punches for Punching Metal and other Material, of which the following is a specification.

This invention relates to punches for punching holes in iron, steel, and other materials; and its object is to provide a punch which, for a hole of given character in material of given thickness, may be operated with less power, less liability to crack or injure the material, and departure from the size and shape of the punch than has been found practicable with punches of the ordinary kind and character, and also one which will itself be less liable to injury—in other words, more durable when subjected to the stress of actual use under severe conditions. For this purpose punches have been made with a supplemental cutting - shoulder produced by reducing the diameter of what would otherwise be the acting end of the punch by turning the same down to form a sharp circumferential edge on the flat face of a perfectly-cylindrical shoulder, the object being to remove the metal by co-operating successive cutting actions of the cutting-edges of a single punch, whereby to avoid the ragged surface or edge produced by the tearing action of a punch having a single face cutting-edge. In such construction, the face of the cutting-edge of greatest diameter joins the cylindrical surface of the cutting-edge of least diameter with a sharp angle, so that the action of both cutting-edges upon the metal is alike. Punches have also been made with a cylindrical body surrounded by a second cutting-edge of undulating or scalloped form, so that in reaming the metal around the punched hole the shearing thereof will be borne equally by the downward projections of said second cutting-edge. Our improvement comprises a punch having successive punching-edges formed on flat faces of unequal diameter, and joining each other by an outwardly inclined or curved wall, in order that the cutting-edge of least diameter will operate not only to remove the central por-

tion of the material from the space to be punched, but also operate to bend the remaining portion of the metal to be removed, and thereby to crack and break away the hard scale from the surface of such remaining portion of the metal, and thus expose the soft or unscaled surface to the action of the succeeding cutting-edge, which determines the size of the hole, and which is thereby caused to cut with much less resistance and to produce a smoother edge around the hole. In this important particular the first acting cutting-edge of least diameter operates in a different manner from the finishing cutting-edge, and gives an advantage not hitherto attained by punches having successive cutting-edges. A conical projection is formed upon the face of the cutting part of least diameter, and its relation to such cutting-edge is such as to bend the metal before receiving the action of said cutting-edge, so as to break the scale and render the cutting easier, while at the same time such projection serves the function of the center holding-point common in punches for punching metal.

Figure 1 is a side view of a punch embracing one portion of my said invention. Fig. 2 is a side view; Fig. 3, a longitudinal sectional view, and Fig. 4 a face view, of a punch, embracing also an additional feature of my said invention.

A is the cylindrical body of the punch, which said body need not differ materially from that of punches in common use, and is provided with or constructed for the use of any suitable means of attaching it to the movable head of a punching-press. It is of course to be understood that the punch is to be used in connection with a suitable bench or support for holding the material to be punched, and furnished with a suitable die for acting in conjunction with the punch during the operation of the latter. As this support, die, &c., may be of any ordinary kind or character and designed to act in the ordinary manner in relation to the punch, such support, die, &c., need not be here specifically described. The face, however, of the punch is of novel construction, being provided with successive punching-edges—two or more, joined by a curved wall—which act in succession upon the ma-

terial to be punched, so that the latter offers less resistance at any one moment of time during the operation of punching than is possible where a single cutting-edge is required to 5 at once part the material around the whole circumference of the hole or opening to be made. Furthermore, the punch constructed according to my said invention, with the curved wall intervening between the cutting-edges, 10 when operating on iron, rolled steel, and the like, loosens the scale upon the surface of the material and causes the same to "chip" or "scale" off, leaving the naked and comparatively soft metal exposed to the action of the larger or 15 circumferential cutting-edge of the punch, thereby greatly lessening the power required to drive the said edge through the material. As represented in Fig. 1, the face of the 20 punch is formed with a central projecting portion of less diameter than the face of the punch itself, this portion having a cutting-edge, *a*, which should be substantially concentric with the circumferential cutting-edge *b* of the punch, and join it by a curved wall, *e*, as shown. 25 When the punch is forced against the material to be punched, the edge *a* acts first, and not only removes a central portion of the material from the space to be punched, but also cracks and breaks away the hard scale from the 30 rounding portions. The cutter, being deprived of support from the central portion, now removed, of the material, and also exposing its naked or unscaled surface, affords much less resistance to the succeeding action of the edge 35 *b*, which determines the size of the hole. Furthermore, owing to this diminished resistance to the action of the edge *b*, less material is torn away from the under side of the hole, and the latter is consequently more nearly cy- 40 lindrical than is commonly attained by the use of the common punch. Thus, for example, where the common punch is used in punching a three-quarter-inch hole in three-quarter-inch steel, one end of the hole is enlarged three- 45 eighths of an inch more than the diameter of the punch, whereas with my invention such

enlargement does not exceed one-eighth of an inch. In order to obtain, however, the most advantageous operation of my said invention, I provide at the center of the part *A* a projecting conical teat or projection, *c*, which, by bending the material into a conical cavity at the center of the part to be punched out, bends said material at such portions into such position that it may be most advantageously sheared by the successive action of the edges *a* and *b*. When desired, the face of the punch may be provided with more than one additional cutting-edge *a*, arranged within its circumferential cutting-edge *b*. 55

It will be seen that the conical projection *c* not only serves the purpose of the holding-point common in flat-faced punches, but has such relation to the cutting-edges of least diameter as to prepare the metal to receive 60 the first cut by bending it into a conical cavity at the center part to be punched, and thus serve to break the surface scale and render the cutting easier. For this purpose the base of the conical projection *c* extends to near the 65 cutting-edges *a*, and the extent of the projection is sufficient to give the required depression of that portion of the metal which is removed by the cutting part of least diameter. 70

What we claim as our invention is— 75

1. That improvement in metal-punches which consists in forming the body with successive annular punching-edges *a* *b*, joined by an outwardly inclined or curved wall, *e*, as described, for the purpose set forth. 80

2. The metal-punch herein shown and described, having the successive annular punching-edges *a* *b*, joined by a curved wall, *e*, and a cone projection, *c*, having the described relation to the cutting-edge of least diameter, 85 for the purposes specified.

EDWARD W. BRIGGS.
JOHN D. WALTON.
